UNITED STATES PATENT OFFICE.

ADELBERT PAUL GERHARDT, OF CHICAGO, ILLINOIS, ASSIGNOR TO WESTERN ELECTRIC COMPANY, INCORPORATED, OF NEW YORK, N.Y., A CORPORATION OF NEW YORK.

MECHANISM FOR WORKING PULPOUS MATERIAL.

Application filed January 23, 1923. Serial No. 614,353.

This invention relates to improvements in mechanism for working pulpoous material, and more particularly to mechanism for forming such material to constitute a homogeneous coating for cores such as rod, wire, and the like.

An object of the invention is to provide a forming mechanism which will operate upon the pulpoous material so as to form it into a homogeneous and uniform coating.

Another object of the invention is to produce such a forming mechanism which may be adjusted to regulate the pressure that is exerted on the coating material during the forming operation and thus control the density of the formed coating.

Still another object of the invention is to provide a forming mechanism which may be operated at high speed and will not strip the coating material from the core during the forming operation.

Other objects and advantages of the mechanism will more fully appear from the following description.

Mechanisms made in accordance with this invention are particularly well adapted for use in connection with the method and apparatus for coating cores disclosed in the co-pending applications of Walker and March Serial No. 547,923, filed March 29, 1922, and Serial No. 547,924, filed March 29, 1922, respectively, but it is to be understood that the invention is not limited to such use but only in so far as defined by the appended claims.

The drawings illustrate one embodiment of the invention in which,

Fig. 1 is a side elevation, partly in section, of a forming mechanism embodying the features of the invention;

Fig. 2 is a vertical sectional view taken on the line 2-2 of Fig. 1;

Fig. 3 is a horizontal view taken on the line 3-3 of Fig. 1;

Figs. 4 and 5 are enlarged vertical sectional views, showing the form of the pulp coating as it is delivered from the liquid containing pulp and the squeezing rolls respectively, and

Figs. 6 and 7 are enlarged vertical sectional views showing the form of the pulp coating during the forming operation and

after the completion of the forming operation respectively.

Mechanisms made in accordance with the present invention are designed to work pulpoous material applied to a core and are particularly adapted to operate in conjunction with the apparatus shown in the co-pending application of Walker and March, Serial No. 547,924, filed March 29, 1922. This apparatus, briefly described, comprises a drum for passing the core through a liquid containing pulp in such manner that pulp is applied to the core as shown in Fig. 4, the coated core then being passed between squeezing rolls 65 which serve to form the pulp coating into a thin ribbon extending at opposite sides of the core, as shown in Fig. 5. For a detailed description of the operation of this apparatus reference is made to the co-pending application above referred to.

The forming mechanism embodying the features of the present invention is designed to receive the coated core from the squeezing rolls and wrap the projecting edges of the ribbon around the core and around each other until it conforms substantially to the shape of the core, the appearance of the coating after it is first acted upon by the former and after the forming action is completed being shown clearly in Figs. 6 and 7.

The former comprises two cup shaped collars 10 and 11 held together in spaced relation by means of rods 12. Integral with each of said collars 10 and 11 is a sleeve 13 and 14 respectively which are rotatably mounted in suitable bearings. A pulley (not shown) may be secured to either of the sleeves 13 or 14 and serves as means for driving the forming mechanism. Two plates 15 and 16 have projecting tongues which are bent around two of the rods 12 to pivotally support the plates in opposed relation to each other, as shown in Fig. 2. Compression springs 17 engage the rear faces of each of the plates 15 and 16 and tend to force them together. The springs 17 are put under the requisite compression by means of adjusting screws 18 which are mounted in brackets 19 secured to the rods 12. The ends of the plates 15 and 16, which are adapted to first receive the coated core, are

flared outwardly so as to gradually wrap the edges of the ribbon around the core without stripping it from the core as it enters the forming plates 15 and 16 through the sleeve 13. The core passes from the forming plates through the sleeve 14.

The forming plates 15 and 16 are rotated rapidly around the core and pulp coating by the means previously referred to, and the 10 said plates wrap the projecting edges of the pulp ribbon around the core and about each other in much the same manner as though the core and pulp ribbon were rolled on a table top with the palm of the hand.

15 In order to make the coated core uniform and control the density of the coating, an adjustable stop is secured to each of the plates 15 and 16 in such position as to abut the opposite forming plate in the manner 20 shown in Fig. 2. Each of the stops comprises a lug 21 having a threaded shank 22 threaded within an opening in each of the plates 16 and 17. Lock nuts 23 serve to hold the shank in any adjusted position. 25 These stops limit the amount of pressure that may be exerted upon the coating material by the forming plates 15 and 16 as they are pressed thereagainst by the springs 17. By adjusting these stops, this pressure 30 may be set at the desired degree. The stops may be adjusted so that after the ribbons are wrapped around the core they engage the outer periphery of the formed coating lightly and thereby do not tend to strip it 35 from the core. In the event that, due to any cause, the coating presented between the plates is considerably thicker than the stops can accommodate, the enlarged portion of the core will spread the plates 15 and 16 40 against the compression springs 17 to allow its passage between the plates.

It will readily be understood that the density of the coating is also controlled by the adjustable stops, since they may be set to 45 permit light or heavy pressure upon the core after the wrapping operation is completed.

What is claimed is:

1. In a mechanism for working pulpos 50 material on a core in strand form so that the said material constitutes a coating for the core throughout its entire length, a member engaging said material to shape it around the core, means tending to move said member into engagement with the core, and means for spacing said member a predetermined distance from the core.

2. In a mechanism for working pulpos 55 material on a core so that the said material constitutes a coating therefor, a positively rotated member engaging said material to wrap it around the core, means tending to move said member into engagement with the core, and means for spacing said member a predetermined distance from the core.

3. In a mechanism for working pulpos 60 material on a core so that the said material constitutes a coating for the core, a rotatable plate-like member engaging said material to shape it around the core, means tending to move said member into engagement with the core, and means for spacing said member a predetermined distance from the core.

4. In a mechanism for working pulpos 65 material on a core so that the said material constitutes a coating for the core, while traveling in substantially a straight line, a member engaging said material to shape it around the core, means tending to move said member into engagement with the core, and means for spacing said member a fixed, predetermined distance from the core.

5. In a mechanism for working pulpos 70 material on a continuously advancing elongated core so that the said material constitutes a coating for the core, a rotatable member engaging said material to shape it around the core, means tending to move said member into engagement with the core and adjustable means for spacing said member a 75 fixed, predetermined distance from the core.

6. In a mechanism for working pulpos 80 material on a core so that the said material constitutes a coating therefor, a rotatable member, said member disposed to normally engage the core during its rotation around the core for progressively forming said material on the core, and means for spacing said member a predetermined distance from the core.

7. In a mechanism for working pulpos 85 material on a core so that the said material constitutes a coating therefor, a pair of rotatable members engaging said material on opposite sides of the core to shape the material around the core, said members disposed to normally engage the core during a 90 rotation thereof, and means for spacing said member a predetermined distance from the core.

8. In a mechanism for working pulpos 95 material on a core so that the said material conforms to the shape of the core, a pair of members engaging said material on opposite sides of the core to shape the material 100 around the core, and means for spacing said members a predetermined distance apart.

9. In a mechanism for working pulpos 105 material on a core so that the said material constitutes a coating therefor, spring pressed rotatable members engaging said material on opposite sides of the core to shape the material around the core, and means for spacing said members a predetermined distance apart.

10. In a mechanism for working pulpos 110 material on a core so that the said material conforms to the shape of the core, spring pressed members engaging said material on opposite sides of the core to shape the ma- 115

terial around the core, and means for spacing said members a fixed, predetermined distance apart.

11. In a mechanism for working pulpos material on a core so that the said material conforms to the shape of the core, members engaging said material on opposite sides of the core to shape the material around the core, and a stop carried by one of said members and engaging the other to space said members a predetermined distance apart.

12. In a mechanism for working pulpos material on a core so that the said material conforms to the shape of the core, members engaging said material on opposite sides of the core to shape the material around the core, and an adjustable stop carried by one of said members and engaging the other to space said members a predetermined distance apart.

13. In a mechanism for working pulpos material on a core so that the said material constitutes a coating therefor, spring pressed rotatable plate-like members engaging said material on opposite sides of the core to

shape the material around the core, and a stop carried by each of said members and engaging the other members for spacing said members a predetermined distance apart.

14. In a mechanism for working pulpos material on a core so that the said material conforms to the shape of the core, spring pressed members engaging said material on opposite sides of the core to shape the material around the core, and a stop carried by each of said members and engaging the other member for spacing said members a predetermined distance apart.

15. In a mechanism for working pulpos material on a core so that the said material conforms to the shape of the core, spring pressed members engaging said material on opposite sides of the core to shape the material around the core, and an adjustable stop carried by each of said members and engaging the other member for spacing said members a predetermined distance apart.

In witness whereof, I hereunto subscribe my name this 12 day of January A. D., 1923.

ADELBERT PAUL GERHARDT.
